(57) CLAIM

I claim the ornamental design for a sports ball, as shown and described.

DESCRIPTION

FIG. 1 is a perspective view thereof;

FIG. 2 is a left side view thereof;

FIG. 3 is a front view thereof;

FIG. 4 is a bottom view thereof; and,

FIG. 5 is a top view thereof.

The broken lines showing the surface indicia on the top of the ball are for illustrative purposes only; and form no part of the claimed design.
